UNITED STATES PATENT OFFICE.

WILLIAM H. ELLIOT, OF NEW YORK, N. Y.

BREECH-LOADING FIRE-ARM.

SPECIFICATION forming part of Letters Patent No. 314,570, dated March 31, 1885.

Application filed January 16, 1885. (No model.)

To all whom it may concern:

Be it known that I, WM. H. ELLIOT, of New York, county of New York, and State of New York, have invented a new and Improved 5 Breech-Loading Fire-Arm, of which the following is a specification.

The object and nature of my invention may be described as follows:

The object of my invention is to provide a 10 simple, cheap, and practicable breech-loading fire-arm that may be charged from a magazine or by hand with equal facility; and the nature of my invention consists in the novel assemblage of certain co-operative devices, which 15 are fully set forth in the following specification and claims. I attain these objects by the mechanism illustrated in the accompanying drawings, in which—

Figure 1 is a vertical longitudinal section 20 of the receiver and guard-strap of the arm, showing the limb-work in elevation. Fig. 2 is a bottom view of the rear end of the receiver. Fig. 3 is a vertical longitudinal section of the guard-strap. Fig. 4 is an elevation of the rear 25 end of the receiver, showing the tangs in section. Fig. 5 is an elevation of the connecting-strap and handle. Fig. 6 is a vertical cross-section of the arm at open lines x , Fig. 1. Fig. 7 is a bottom view of the brace. Fig. 30 8 is an elevation of the rear end of the bolt and parts adjacent thereto. Fig. 9 is a plan of the connecting-strap. Fig. 10 is a plan of the guard-strap.

My invention refers to that class of arm 35 having a bolt for closing the chamber, which moves in a line with the barrel and is operated through the medium of a reciprocating strap and handle arranged under the wrist of the arm.

40 My improved arm may be charged from a magazine located under the barrel and provided with such carrying devices as are shown in my patent of February 12, 1884, No. 293, 315. It may be charged from a magazine located on the top of the receiver in the manner shown in my patent of November 4, 1884, No. 307,531, or it may be charged by hand. The bolt has a pendent portion, c' , at its forward end. To this pendent portion the brace 45 is pivoted at c'' .

The recoil-shoulders o for supporting the brace should be formed in one piece with and

should project from the inner surface of the receiver. They may, however, be made in separate pieces and attached to the receiver by means of strong screws, a portion of each recoil-shoulder projecting through the side of the receiver to prevent their displacement by the recoil; or they may be formed upon a suitably-supported guard-strap, as shown in my patent of September 18, 1883, No. 285,020; and whether supported by the receiver or by the guard-strap they should extend far enough to the rear to form the ledge o' , between which and the ledge o'' the friction-roll e'' runs to prevent friction of the brace on said ledges during the manipulation of the arm. The reciprocating strap i is held to a substantially parallel movement at its forward end by its connection with the arm e of the brace at i' , and it is guided at its rear end in a direction substantially parallel with the wrist of the arm by the diagonal mortise m' in the guard-strap, through which it slides in manipulating the arm. This mortise is cut through the guard-strap in the direction, as near as practicable, of the wrist of the arm. The reciprocating strap has a handle, e'' , at its rear end, by which means the arm is operated. It should also be provided with a friction-catch to hold the arm closed, as shown in several of my patents.

In operation a rearward movement of the handle first raises the rear end of the brace above the recoil-shoulders and then draws the bolt and brace backward to the position shown in Fig. 1 by open lines. A reverse movement of the handle pushes the brace and bolt forward and brings the brace down in front of the recoil-shoulders, as shown in full lines, 90 Fig. 1. The brace e has a roller, e'' , with a pivotal bearing on its rear end which runs between the ledges o' and o'' . This roller is large enough in diameter to project a little both above and below the brace, and so prevents friction of the brace on the ledges while manipulating the arm. The recoil-shoulders are arranged one upon each side of the receiver at some distance apart to make room for the arm e of the brace to pass to the rearward between them. The connecting-strap i has a long recess, h' , in and through which the trigger performs its functions. The brace is made wide enough to fill the entire space between

the two sides of the receiver, and has a central cut in its forward end to make room for the pendant c' of the bolt, between which and the brace there is a bearing-surface concentric with the pivot c'' . It also has the arm e' centrally attached at a point directly forward of the cut for said pendant. By this construction all the parts within the receiver are centrally arranged. The roller n has a diagonally-elongated pivotal bearing in the rear end of the bolt, the pivot being driven fast in the roller and moves back and forth in the diagonal bearing or slot n' . When the bolt makes the backward movement in operating the arm, the hammer crowds the roller downward and forward to the position shown in Fig. 1 in full lines, and as the roller in this position passes over the nose of the hammer it depresses that device a little more than is necessary to bring it to full-cock. When the nose of the hammer has passed the roller, it rises a little until the sear rests in the full-cock notch, the nose of the hammer nearly touching the under side of the bolt. As the bolt moves forward in closing the arm, the nose of the hammer pushes the roller upward and backward to the position shown in Fig. 8, and does not depress the hammer during that movement of the bolt, whereby the friction caused by cocking the hammer is considerably reduced during the backward movement of the bolt, and does not occur at all during its forward movement.

By providing the handle i'' with guides in the lower side of the guard-strap it may have a movement exactly parallel with the wrist of the arm. In this case the diagonal mortise m' should be made somewhat larger, so that it may not interfere with the movement of the strap i , which would have to be joined to the handle by means of a joint, as at open lines i''' , Fig. 5.

Figs. 2 and 4 show a modification of the invention in which the reciprocating strap is guided at its rear end by means independent of the guard-strap or other devices supported by the receiver. The space between the two sides of the receiver is narrowed at its rear end, as at r'' , Fig. 2, and the grooves o''' , Fig. 4, cut therein. The reciprocating strap slides in and is guided by these grooves without coming in contact with the guard-strap. That portion of the reciprocating strap between the open lines r and r' may be removed. Still the recess in and through which the trigger operates will remain.

Open lines r'' , Fig. 3, show the direction of the mortise in the guard-strap, through which the reciprocating strap slides and by which it is guided.

Having described my invention, what I desire to have secured to me by Letters Patent of the United States is—

1. In a breech-loading fire-arm, the combination of devices, substantially as follows: a

bolt for closing the chamber, a brace for locking said bolt, pivoted at its forward end to the forward end of the bolt, and provided with an operating-arm, a divided recoil-shoulder within the receiver, against which said brace engages in locking the bolt, a slot extending backward from between said shoulders, through which said operating-arm travels to move the bolt, a reciprocating handle, and connecting-strap, guided by suitable means at its rear end and connected at its forward end to said operating-arm, said reciprocating strap being constructed with recess h' , in and through which the trigger operates upon the hammer, as set forth.

2. In a breech-loading fire-arm, the combination of devices, substantially as follows: a bolt for closing the chamber, a brace for locking said bolt, pivoted at its forward end to the forward end of the bolt, and provided with an operating-arm, a divided recoil-shoulder within the receiver, against which said brace engages in locking the bolt, a slot extending backward from between said shoulders, through which said operating-arm travels to move the bolt, a reciprocating handle, and connecting-strap, guided at its forward end by its connection with said arm and at its rear end by a diagonal mortise in the guard-strap, through which it slides in a direction substantially parallel with the wrist of the arm, as shown and described.

3. In a breech-loading fire-arm, a bolt for closing the chamber, which moves in a line with the barrel, a hammer pivoted in the receiver and provided with the usual mainspring and trigger, said hammer being brought to full-cock by the bolt in its backward movement, and in combination therewith a friction-roller provided with diagonally-elongated pivotal bearing in the rear end of said bolt, whereby the hammer is depressed beyond full-cock by the backward movement of the bolt, but is not depressed at all by its forward movement, substantially as specified.

4. The combination, in a breech-loading fire-arm, of the ledges o' and o'' , projecting inward from the inner surface of the receiver, one above and one below the path of the locking-brace, a bolt for closing the chamber, which moves in a line with the barrel, a brace for locking the same, which is pivoted at its forward end to the forward end of said bolt and is provided with an operating arm and handle with a suitable connection between the same, said brace being provided at its rear end with friction-roll e' , which runs alternately on ledges o' o'' as the bolt is moved back and forth, substantially as and for the purpose specified.
